UNITED STATES PATENT OFFICE.

FRANK D. SHEPHERD, OF SALT LAKE CITY, UTAH.

PUPPET-VALVE FOR INTERNAL-COMBUSTION ENGINES.

1,263,133.

Specification of Letters Patent. Patented Apr. 16, 1918.

Application filed October 20, 1917. Serial No. 197,526.

To all whom it may concern:

Be it known that I, FRANK D. SHEPHERD, of Salt Lake City, in the county of Salt Lake, and in the State of Utah, have invented a certain new and useful Improvement in Puppet-Valves for Internal-Combustion Engines, and do hereby declare that the following is a full, clear, and exact description thereof.

10 My invention relates to puppet valves for internal combustion engines and more particularly has to do with the spring device for seating the valve. My object generally stated is to facilitate the cleaning of parts 15 apt to be gummed and to cause sticking and to oil the same and also to render more accessible the parts for removal and replacement, and with this object in view my invention consists in the construction substantially hereinafter specified and claimed.

20 In the accompanying drawings:

Figure 1 is a vertical section of enough of an internal combustion engine to illustrate one embodiment of my invention,

25 Fig. 2 is a detail view in side elevation of certain parts shown in Fig. 1,

Fig. 3, is a view similar to Fig. 1, of another embodiment of my invention,

30 Fig. 4, is a detail view in side elevation of one of the members shown in Fig. 3,

Fig. 5 is a view similar to Figs. 1 and 3 of still another embodiment of my invention,

35 Fig. 6 is a view in side elevation of the upper portion of the spring container shown in Fig. 5, but with a different form of head for the container-closing plug,

Fig. 7 is a detail view in vertical section of parts corresponding with those shown in Fig. 6 excepting that a different form of closure 40 for the hole in said plug is illustrated,

Fig. 8 is a detail view in vertical section showing a form of the valve for controlling admission to the spring container different from what is shown in the other figures.

45 Fig. 9 is a top plan view of one of the spring containers or shells showing a formation of the upper end thereof for the application of a wrench.

Referring to the drawings 10 designates 50 the engine cylinder, 11 the head thereof (which may be separate from and bolted to the cylinder as shown in Fig. 1 or integral with the cylinder as shown in Figs. 3 and 5), 12 the valve controlling either the inlet or 55 exhaust and being lifted from its seat 13 by a cam (not shown) and returned to and

yieldingly held upon its seat by a coil spring 14 that is situated within and housed by a cylindrical shell or container 15 that is screwed at one end into a threaded hole in 60 the cylinder head 11. The spring at one end presses upon a flange or collar 16 upon a stem 17 that passes through a guide hole in the portion of the spring container 15 that is screwed in the cylinder head and reaches to 65 or is connected with the valve 12 so as to transmit through it the pressure of the spring. The stem 17 may be unconnected with the valve 12 as shown in Fig. 1, or it may be integral therewith as shown in Fig. 70 3; and the collar 16 may be integral with the stem 17 as shown in Fig. 1, or loose therefrom as shown in Fig. 3 and slipped over the reduced upper extremity of the stem and bearing upon a shoulder upon the stem 75 formed by such reduction. The collar 16 as clearly shown in Fig. 3 has several holes or perforations 18 running through it from top to bottom for the passage of air during the vertical movement of the collar to avoid 80 movement being hindered by air pressure, or suction within the container 15, the interior of which under normal conditions is closed in an air tight manner to the external air.

85 The upper or outer end of the container is closed by a removable cap 19 screwed thereto and having a flange 20 which overlaps the outer end of the container 15 and between which and the adjacent surface of the latter is placed a gasket 21.

The cap 19 is perforated from end to end by a central hole 22, at the inner end of which is a valve seat 23 which as shown in Figs. 1 and 3, is inwardly beveled or conical 95 and with which coacts a valve 24, which when on the seat closes communication between the interior of the spring container 15 and the outside. Projecting from the valve 24 into the hole 22, is a hollow stem or guide 100 25 which may have the cup form shown in Fig. 1 with a number of small holes or perforations 26 through its side walls close to the valve; or it may have the form shown in Fig. 3 in which instead of the holes 26 there are 105 elongated slots 27 which serve the same purpose as the holes, but separate the stem into a series of distinct fingers. On its opposite side the valve 24 has a cylindrical block or plug 28 that extends partially through the 110 coil spring 14 and serves as a filler to reduce the volume of the space in the shell or con-

tainer 15, and thus diminish its capacity for holding gas which might leak past the stem 17 thereinto and also constitutes a lateral support or guide for the spring so as to prevent unbalanced sidewise pressure upon the valve 12. The end of the spring 14 opposite that which bears upon the collar 16 bears upon an angular flange 29 integral with and between the filler plug 28 and the valve 24 10 and thus the one spring 14 acts upon both valves 12 and 24 yieldingly to hold the same to their respective seats. It will be observed that in a single member I provide the valve 24 to close the container air and gas tight to 15 the outside air, the plug 28 which serves the two functions of a filler and a guide or support for the spring 14, and the bearing head 29 for one end of the spring.

The hole 22 of the cap 19 is closed against 20 the entrance of dirt or dust by a removable filling plug or cover which may have the form of the thimble 30, shown in Figs. 1 and 2, which is inserted in the hole and held thereby by friction, one or more slits 31 being 25 provided in the side of the thimble to give it the desired elasticity; or it may have the form of the screw plug 300 shown in Fig. 3 that is screwed into the outer end of the hole 22. Again as shown in Figs. 5 and 6 30 the hole closure or cover may be in the form of a spring pressed pivoted plate 301 that may be swung to uncover the hole 22, the spring 302 serving to press it with sufficient force to seal or close the opening and 35 yet allowing the slight vertical movement necessary to engage or disengage it with the latch pin 303. When the closing plug or plate is removed from the outer end of the hole it will be seen that by some suitable 40 instrument thrust in the hole 22 the valve 24 may be pushed down off its seat and oil thereby admitted to the interior of the container 15 to find its way to the surfaces below needing lubrication; or if the parts are 45 gummed a little coal oil or other suitable material may be introduced into the container to find its way to the gummed surfaces and the engine then run a few minutes so as to effect the cleaning of the parts 50 by action of the coal oil or the like thereon.

As shown in Fig. 1 the filling plug 28 may be made hollow to secure lightness; or as shown in Fig. 3 it may be made solid and as it is desirable to give it a length as 55 great as possible without interfering with the proper lifting of the valve 12, it may be provided in its lower end as shown in Fig. 3 with a hole 32 to pass over the upper end of the valve stem 17 when the same as 60 shown in Fig. 3 is projected above the collar 16 to receive a grinding tool. As shown in Fig. 5 the filling plug 28 is also hollow and it opens up into the guide stem 25 and in this case a filling 280 of some light mate- 65 rial is placed in the chamber in the filling

plug 28 in order to prevent the accumulation of oil therein.

Preferably, but not necessarily in all cases, a thin disk 33 is placed in the bottom of the container 15 below the collar 16 and its thickness is such that it does not fill the entire space below the collar 16 for the underside of the collar 16 must not touch any surface as should it do so it would prevent seating of the valve. Thus the bottom 75 of the chamber in the container 15 is sufficiently below the collar 16 as to assure ample clearance space and then to take up any unnecessary space the disk 33 is provided. By making the disk 33 of material that is 80 a nonconductor of heat said disk has the additional utility of protecting the spring from injurious high temperatures which might destroy its temper.

As shown in Figs. 3 and 5 where the valve 85 stem 17 is integral with the valve 12 they are joined by a fillet 34 which is concavely curved and to accommodate said fillet on the lifting of the valve the underside of the shell or container 15 may have a correspondingly shaped recess 36 which however immediately adjacent the valve stem has a flat or plane surface 37 that assures the scraping off of any deposits on the valve stem and prevents their entrance into the valve 95 stem guide opening.

As shown in Figs. 5 and 7 the valve seat 230 on the filling cap 19 is not beveled or conical, but is a plane surface on the inner end of the cap and the valve 240 is similarly shaped and as shown in Fig. 8 while the conical form of seat and valve are employed they have the reverse arrangement shown in Figs. 1 and 3, that is to say the seat is on a surface projecting from the cap 100 19 and the valve is concaved or dished, but this is not as desirable a form as the other because it tends to trap or collect oil or other liquid introduced through the cap hole 22.

The top or outer end of the shell or container 15 is given a form or construction for the application of a turning tool for screwing the container into its hole in the cylinder head or removing it therefrom. 115 This renders possible the removal of any one of a gang or series of containers without disturbing the others whereas with the tool engaging portion close to the cylinder head it is impossible by reason of the nearness 120 together of adjacent containers to get access to any one without removing adjacent ones. Preferably I flatten the outer side of the container 15 at its outer end so that a socket wrench may be readily applied thereto; and if desired as illustrated in Fig. 6, the flange 200 of the cap 19 may be similarly formed so that the same socket wrench will serve for the cap as well as for the container itself. As shown in Fig. 6, the cap hole is 130

provided with a pivoted cover plate as in Fig. 5; while as in Fig. 7, the cap hole 22 is closed by the screw plug as in Fig. 3, and a gasket 38 is placed between the head of the 5 plug and the top of the cap around the hole 22 to make a gas and air tight joint at such point.

It is to be understood however that I do not limit myself to the described form 10 or location of the means for the application of a tool to the container unless the same is specifically set forth in the appended claims.

The stem on which the cam acts to lift the valve from its seat may, as shown in 15 Figs. 1 and 5 be integral with the valve 12, or separate therefrom as shown in Fig. 3. When made separate from the valve as shown in Fig. 3 it is simply a straight rod 39 of the right diameter to give the desired 20 bearing surface at its ends and its ends may be case-hardened or tempered to prevent wear or upsetting thereof. This is a cheaper construction than the double integral one and provides a strong stem that will not 25 warp and which will satisfactorily perform its duty. I, therefore, consider myself at liberty to employ either a separate construction of stem and head or an integral construction.

30 From the variety of the embodiments of my invention that I have shown it will be seen that my invention is not restricted to the details of construction and it may be carried out with great variety of form or 35 design of parts. My invention is applicable to internal combustion engines whether of the L-head or the T-head type and whether they are vertical or horizontal. If desired the shells or containers 15 instead of being 40 made in the single or individual form screwed to the cylinder head can be made in blocks or groups as illustrated in my application No. 147,396, filed February 8, 1917. They may, as shown in the drawings, have 45 air cooling ribs or fins or be made smooth.

By my invention the parts are quickly accessible, fuel is economized, wear of the valve stem on one side causing the valve to cock on its seat and cause leakage is 50 avoided because the valve movements are in a straight line both under the power of the cam and the action of the seating spring and as the valves can turn freely when working they automatically dislodge carbon and foreign matter from the faces which if not displaced causes pitting or grooving and leaking.

Having thus described my invention what I claim is:

60 1. As an improvement in puppet valves for internal combustion engines, the combination of a valve, a spring for yieldingly holding the valve to its seat, means for transmitting pressure of the spring to the valve, a shell or container housing the 65

spring, an opening leading outward from said container having at its inner end a valve seat and an inwardly moving valve in the container normally held to said seat.

2. As an improvement in puppet valves 70 for internal combustion engines, the combination of a valve, a spring for yieldingly holding the valve to its seat, means for transmitting pressure of the spring to the valve, a shell or container housing the 75 spring, and a valved opening leading outward from said container, the valve for said opening being yieldingly held to its seat by said spring.

3. As an improvement in puppet valves 80 for internal combustion engines, the combination of a valve, a coil spring for yieldingly holding the valve to its seat, means for transmitting pressure of the spring to the valve, a shell or container housing the 85 spring, a valved opening leading outward from said container, the valve for said opening being yieldingly held to its seat by said spring, and a filling plug extending from the valve into the coils of the spring. 90

4. As an improvement in puppet valves for internal combustion engines, the combination of a valve, a coil spring for yieldingly holding the valve to its seat, means for transmitting pressure of the spring to the 95 valve, a shell or container housing the spring, a valved opening leading outward from said container, the valve for said opening being yieldingly held to its seat by said spring, and a filling plug extending from the 100 valve into the coils of the spring, said filling plug being hollow.

5. As an improvement in puppet valves for internal combustion engines, the combination of a valve, a spring for yieldingly 105 holding the valve to its seat, means for transmitting pressure of the spring to the valve, a shell or container housing the spring and a valved opening leading outward from said container, the valve for said container having a hollow perforated stem extending into 110 said opening beyond the valve seat.

6. As an improvement in puppet valves for internal combustion engines the combination of a valve, a spring for yieldingly holding the valve to its seat, means for transmitting pressure of the spring to the valve, a shell or container housing the spring, a valved opening leading outward from said container, and means to close said valved 115 120 opening at a point beyond the valve.

7. As an improvement in puppet valves for internal combustion engines the combination of a valve, a spring for yieldingly holding the valve to its seat, means for transmitting 125 pressure of the spring to the valve, a shell or container housing the spring, and a removable cap in the outer end of said container having a valve controlled opening passing through it. 130

8. As an improvement in puppet valves for internal combustion engines the combination of a valve, a spring for yieldingly holding the valve to its seat, means for transmitting pressure of the spring to the valve, a shell or container housing the spring, and a removable cap in the outer end of said container having a valve controlled opening passing through it, the valve for controlling said opening being held to its seat by said spring.

9. As an improvement in puppet valves for internal combustion engines the combination of a valve, a spring for yieldingly holding the valve to its seat, a shell or container for the spring, a stem passing through an opening in the inner end of said container and reaching to the valve, a collar on said stem within the container upon which one end of the spring bears, an opening leading through

the outer end of the container, a valve for said opening and a bearing on said valve for the other end of said spring.

10. As an improvement in puppet valves for internal combustion engines the combination of a valve, a coil spring for yieldingly holding the valve to its seat, a shell or container for the spring, a stem passing through an opening in the inner end of said container and reaching to the valve, a collar on said stem within the container upon which one end of the spring bears, an opening leading through the outer end of the container, a valve for said container, a bearing on said valve for the other end of said spring, and a filling plug extending from said bearing into the coils of the spring.

In testimony that I claim the foregoing I have hereunto set my hand.

FRANK D. SHEPHERD.
